UNITED STATES PATENT OFFICE.

RAOUL VENDÔME, OF PARIS, FRANCE.

ATOMIZER.

Application filed July 6, 1926, Serial No. 120,826, and in France July 31, 1925.

In the atomizers which are in current use for the spraying of liquids, the spraying chamber consists of a nozzle which is separately secured to the head, and into which 5 is inserted the end of the immersed tube, which for this purpose is bent at right angles, or there is employed an intermediate element which is secured to the tube for extending it within the nozzle.

10 The atomizers of this construction offer great drawbacks due to the difficulties found in the manufacture and in the mounting of the separate nozzles as well as of the tubes and like internal parts, and also in the adjustment of such parts to obtain the proper spraying.

20 My invention relates to improvements in atomizers with a view of simplifying their construction and assembling and of facilitating the adjustment of the capacity of the spraying chamber, these improvements essentially consisting in the elimination of the separately secured nozzle and its internal parts, the spraying chamber being now 25 formed by the sprayer head itself.

In the drawings:

Figure 1 is a broken view in vertical section of the improved atomizer.

30 Fig. 2 is a horizontal section on the line 2—2 of Fig. 1, the head of the bottle neck being omitted.

35 The head 1 of the atomizer, which may be mounted in any suitable manner upon the neck of the bottle or like vessel 10, comprises an aperture 2 for the intake of air, with which is connected a flexible tube 3 leading to the bulb. At the top of the head is formed the chamber 4 having an orifice 5 at the side. The immersed tube 6 extends 40 at the top into the chamber 4 whose internal diameter is somewhat larger than that of the tube, so as to form an annular space between these two parts. The said tube is mounted in the head 1 by means of a screw-threaded sleeve 7 having thereon the flat 45 parts 7^a and flanges 8 which bear upon the lower part of the head 1 so as to limit the amount by which the said tube enters the chamber 4, which latter constitutes the 50 spraying chamber.

55 The air which enters through the aperture 2 will proceed into the said head and will exercise a pressure upon the liquid, which thus rises in the tube 6 in the known manner. When the liquid attains the cham-

ber 4 it becomes mixed with the air entering said chamber through the annular space, as shown by the arrows.

The sprayed liquid is projected to the exterior through the small orifice 5 which 60 is substituted for the usual nozzle.

The advantages resulting from this construction of the atomizer are obvious. It comprises no spraying nozzle extending outwardly and secured to the head, nor any 65 fragile or complicated parts serving to form the spraying chamber within the nozzle; the device can thus be manufactured and assembled in a very simple manner, thus affording a great saving in cost.

70 The capacity of the spraying chamber can be regulated with great facility by adjusting the amount by which the said tube enters the chamber.

Obviously, the construction herein represented is given solely by way of example, and the shape and size of the parts may be varied without departing from the spirit of the invention.

75 Since the spray discharge orifice can be disposed at any point on the side wall of the atomizer chamber 4, I obtain an advantage due to the fact that the orifice can be situated exactly opposite the person using the device for spraying perfumes or the like, while the bulb will be situated on the right hand side.

80 The air inlet communicating with the flexible tube 3 may be formed at any part of the head.

85 I claim:

An atomizer including a vessel, a spray head removably secured thereto and extending above the upper end thereof, the lower end of the head being formed with an interiorly threaded opening, an exteriorly threaded member engaging in said threaded opening, said member having a major diameter corresponding to that of the opening and a minor diameter substantially less than that of the opening to provide communicating passages between the interior of the head and the interior of the vessel, said head being interiorly formed to provide an air chamber and having a lateral air inlet port, the upper end of the head being in the form of a tube-like extension materially reduced in diameter as compared with the diameter of said air chamber, said tube-like extension being closed at its outer end and pro-

vided with an opening through its side wall, liquid delivery conduit means carried by said threaded member and extending below the same into the vessel and above the same into the head, the upper end of said conduit means being open and projecting into the tube-like extension to a point spaced a substantial distance below said opening through the side wall of the tube-like extension, the 10 said upper end of the conduit means being

spaced from the walls of the tube-like extension and having its open end positioned to direct its discharge against the outer closed end of said tube-like extension, and means connected with said port for supplying compressed air to said air chamber. 15

Signed at Paris, Seine, France, this twenty-third day of June, A. D. 1926.

RAOUL VENDÔME.
